UNITED STATES PATENT OFFICE.

CHARLES R. EVERSON, OF MACEDON, NEW YORK.

METAL ROOF.

SPECIFICATION forming part of Letters Patent No. 451,650, dated May 5, 1891.

Application filed August 9, 1890. Serial No. 361,523. (No model.)

To all whom it may concern:

Be it known that I, CHARLES R. EVERSON, of Macedon, in the county of Wayne and State of New York, have invented a new and useful Improvement in Anti-Rust Metal Roofs, which improvement is fully set forth in the following specification and shown in the accompanying drawings.

My invention relates to sheet-metal roofs, more particularly tin roofs, for buildings, the design being to produce an anti-rust roof by joining to the sheets of tin small pieces of another metal—as sheet-zinc, for instance—the invention being hereinafter fully described, and particularly pointed out in the claims.

Referring to the drawings, Figure 1 is a portion of a roof, showing my anti-rust tags in place in dotted lines; Fig. 2, an enlarged view of one of the tags, better showing its form and construction; Fig. 3, a cross-section on the line 3 3 in Fig. 2, and Fig. 4 a section on the dotted line 4 4 in Fig. 2. Fig. 5 shows the adaptation of the invention to a standing lock.

Referring to the parts, A are ordinary sheets of roofing-tin, and B the anti-rust tags. The sheets of tin are overlapped and interlocked at their contiguous edges, as shown in Fig. 3, and soldered together when placed upon the roof. The tags I preferably form with a tin backing or holder a, holding a small sheet of zinc b. The upper edge c of the holder a is folded over the zinc and closely hammered down thereon to hold the parts together, and both pieces are pierced at a point near the center of the zinc sheet to receive a nail d to secure the tag to the roof-board C. In piercing these parts the punch passes through the zinc first, and both parts are bent downward or cupped around the hole to receive the head of the nail, as shown in Fig. 4, the cup of the zinc resting in the cup of the tin. This forms an additional means of securing the sheet of zinc to the tin backing, as it tends to prevent a lateral or sliding motion of one piece upon the other. At its lower edge the holder a is turned or hooked under the lip or fold e at the upper edge of the lower sheet A, the holder lying against the roof-board. The adjacent sheet A above is placed over or upon the tag, and, like the latter, is

bent at its lower edge under the fold e of the sheet below it, its lower fold also including the lower part of the tag. When the parts 55 are thus put together and hammered down, each sheet A is over and in contact with the zinc portion of one or more of the tags B. These tags, being secured to the sheet A and nailed to the roof-boards, serve also to secure 60 the tin roof to the roof-boards of the building.

When applied to a standing lock, (shown in Fig. 5,) the holder a of the tag is made long and bent to the form of an L, as shown, the zinc b being laid upon the foot or lower 65 part of the holder, or the part that rests upon the roof-boards. In this construction the upper edges of the respective holders a are bent down over the upturned edges of the respective sheets of tin A and hammered closely 70 down, the lower or under faces of the holders being in contact with the roof-boards.

In constructing the roof I prefer to place two tags at each of the long sides of the sheets of tin A and one at each of the short sides or 75 ends, as shown in Fig. 1. By this construction each sheet of tin is in contact with one or more of the zinc pieces, which serves to prevent the rusting of the sheets of tin.

What I claim as my invention is—

1. A roof consisting of sheets of tin joined at their respective contiguous edges to form a tight covering, in combination with tags formed with pieces of metal other than tin, secured to the edges of each of said sheets 85 of tin in positions to underlie the adjacent sheets of tin and be in contact therewith, substantially as shown and described.

2. A metal roof consisting of sheets of tin locked or joined at their respective contiguous edges, in combination with tags of metal secured to the edges of each of said sheets of tin at the seams between the latter, said tags each consisting of a sheet-metal backing or holder a and strip of metal b other than tin 95 held by said backing or holder, the latter being in contact with one sheet A of the roofing-tin and the part b in contact with the adjacent sheet of roofing-tin, substantially as described, and for the purpose set forth.

3. A roof consisting of sheets of tin joined at their respective edges to form a tight covering, in combination with metal tags secured to the edges of each of said sheets of tin, said

tags each consisting of a sheet-metal holder *a* and strip of metal *b* other than tin, said holder being turned at one edge down over an edge of the part *b*, and a nail piercing said two parts *a* and *b*, the parts or pieces *a* and *b* being cupped to receive the head of the nail, substantially as shown and described.

In witness whereof I have hereunto set my hand, this 24th day of June, 1890, in the presence of two subscribing witnesses.

CHARLES R. EVERSON.
